UNITED STATES PATENT OFFICE.

HERBERT S. WOODWARD, OF CARBONDALE, PENNSYLVANIA.

VIBRATING SCREEN.

Application filed October 28, 1925. Serial No. 65,287.

My invention relates to apparatus for sifting material by effecting vibration of a screen or foraminous plate on which the material is disposed, a principal object of the invention being to provide an apparatus for this purpose embodying features and advantages not found in devices hitherto proposed therefor. To this end my invention contemplates the provision of an inclined screen on which the material to be sifted is disposed, in association with means, including a vertically disposed flexible member rigidly supported at one of its ends, for imparting to the screen a series of impulses in a direction substantially normal thereto so as to effect a positive, rapid, vibratory movement of the screen. My invention further contemplates the provision of means for rapidly flexing or bending the flexible member to and fro in a horizontal direction or plane in association with means for translating the resultant vertical component of the movement so set up in the member to the screen but in an increased amount or amplitude whereby a relatively small vertical shortening or elongation of the member is operative to induce a relatively considerably greater movement of the screen.

Further objects of the invention are to provide means for conveniently adjusting the angularity of the screen; to generally simplify and improve the construction of vibratory screens of the character to which the present invention relates, and to provide an apparatus satisfactorily operative for the performance of its intended function which is simple, yet rugged in construction and not liable to get out of order under the conditions of operation and relatively rough usage to which devices of this general character are ordinarily subjected.

My invention further includes other objects and novel features of design, construction and arrangement to which reference will hereinafter be made or which will be apparent from the accompanying drawings forming a part hereof and in which Fig. 1 is a side elevation of an apparatus constructed in accordance with a preferred embodiment of my invention, a portion of the side wall of the screen frame being broken away to show the screen proper. Fig. 2 is a rear end elevation of the apparatus shown in Fig. 1 and Fig. 3 is a horizontal fragmentary section on line 3—3 in Fig. 1. Fig. 4 is a detail view illustrating a slightly modified construction

of one of the elements of the apparatus and Fig. 5 is an enlarged fragmentary vertical section on line 5—5 in Fig. 3. The same symbols are used to designate identical parts in the several figures.

I am aware that it has hitherto been proposed to effect vibration of a screen through the medium of a vertically extending flexible member attached at one end to the screen and the other to the base of the apparatus in conjunction with means for imparting to the member a horizontal amplitude of vibration, an apparatus of that character being disclosed in U. S. Letters Patent No. 1,411,834, granted April 4, 1922 to John Bland for improvements in screens. In such apparatus, however, in order to effect a vibration of the screen in relatively considerable amplitude it is necessary to impart to the flexible member an excessive horizontal vibration so that while such apparatus is entirely satisfactory for use under conditions in which but relatively small motion of the screen is required, they are more or less impractical for use where a relatively large motion is desired. An important feature and advantage of apparatus constructed in accordance with the present invention, therefore, resides in the ability to therewith effect a relatively considerable movement of the screen with a relatively small horizontal vibratory movement of the flexible member as will hereafter more fully appear.

As shown, the machine or apparatus comprises a base, generally designated as B, and formed by a pair of laterally spaced longitudinally extending side members 1—1 connected near their ends by cross ties 2—2, the base being preferably of relatively heavy construction so as to form a firm support. Respectively disposed above the side members and supported in spaced relation therefrom, preferably as hereinafter described, are a pair of longitudinally extending stringers 3—3 conveniently of wood which may be connected near their ends by cross members 4—4 so as to form a rectangular, open sub-frame, generally designated as F.

I prefer to yieldingly support the sub-frame above the base in any convenient way, for example, by means of vertically directed bolts 5 extending upwardly from near the forward ends of the side members of the base and freely through the ends of the stringers and surrounded by coil springs 6 and 7 dis-

posed above and below the latter, a washer 8 and nut 9 on the upper ends of the bolts affording means for adjusting the tension of the springs. A substantially similar construction may be employed for supporting the rear end of the sub-frame save that a flat spring 10 is shown as utilized in place of the coil spring 7, as under most conditions the use of a flat spring at this point is preferable as tending to prevent lateral movement of the stringers and in turn of the screen during the operation of the machine, such lateral movement being generally undesirable as the same tends to set up certain local vibrations in the screen which are inimical to the accomplishment of the best results.

The material to be sifted is supported upon a screen generally designated as S which may be of any suitable construction, that shown comprising an open, rectangular frame having side and end walls and a bottom of wire mesh. As the preferred construction and arrangement of these parts is clearly evident from the drawing, further description thereof is deemed superfluous save that it may be noted that the frame is provided with relatively longitudinally extending bottom side members 12-12 disposed beneath the wire which are of utility in affording rigidity to the screen and also in furnishing a point for attachment of certain elements of the means by which the screen is supported as herein-after described.

In order that the material may progressively move along the screen under the vibratory action thereof, the latter is supported in an inclined position with its rear end, that is, the end adjacent the right hand side of the sheet when the apparatus is viewed as in Fig. 1 of the drawing, considerably elevated above its forward end, which latter is supported in any suitable way for oscillation about a horizontal axis extending transversely of the apparatus. This support may be conveniently effected by providing a vertically extending pillar 15 adjacent the forward end of each of the stringers 3, the base of the pillar being seated on the upper face of the stringer and securely bolted thereto. As shown in Fig. 1 these pillars are made of wood and each is provided at its upper end with a pillow block 16 while a corresponding inverted pillow block 17 is secured to the under face of the screen, conveniently to the member 12, and a shaft or axle 18 extended through the several blocks, this, or other equivalent arrangement, being operative to permit oscillation of the screen about the axis of the shaft. Instead of employing pillars of wood I may utilize pillars of metal, one form of which is shown in Fig. 4 and which comprises a vertical rod 20 having right and left hand threads on its ends and provided with a hexagonal boss 21 at its center to afford a grip for a wrench. The lower

end of the rod is threaded into a suitable base 22 bolted or otherwise secured to the stringer and the upper end into a head 23 having a transversely disposed bore 24 for the reception of the end of the shaft 18. It will be apparent that if a pillar of this type is employed the vertical height of the shaft above the stringer may be readily adjusted by turning the rod so as to raise or lower the adjacent end of the screen which is frequently of advantage.

The rear end of the screen is supported through the medium of the mechanism by which its vibration is effected and which will now be described. Said mechanism or means comprise a pair of struts 25, 25 firmly supported on each stringer, as by clamps and bolts, generally designated as 26, 27, the lower ends of each pair of struts being spaced relatively far apart and resting on the subjacent stringer, and their upper ends being respectively inclined inwardly toward each other. Between the upper ends of each pair of struts is firmly clamped, as by bolts 28, the upper extremity of a flexible member 30 so that the major portion of the member depends between the struts, it being of course understood that the screen is disposed between the respective pairs of struts and adjacent flexible members. The flexible members 30 are preferably similar in construction and may be made of wood or metal though I prefer to employ the former, and the lower end of each member is pivotally connected in any suitable way to a substantially horizontally extending lever 31 disposed adjacent the subjacent stringer 3 and pivotally connected thereto at its forward end, conveniently through the medium of a pillow block 32 carried by the stringer and a pivot pin or stub shaft 33 extended therethrough and through a boss 31' with which the adjacent end of the lever is provided. The connection between the end of the flexible member and the lever may be made in any suitable way, conveniently by means of a stub shaft or pin 34 extended horizontally through a boss 31" formed on the lever and through a bushing or sleeve 35 secured to the end of the member through the medium of a strap 36 and maintained in position by bolts 37, but any other means for effecting the requisite pivotal connection between the end of the flexible member and the lever may be employed if desired.

The pivotal connection between each member and its lever is preferably made about midway of the ends of the latter, and the rear or free end of the lever is connected with the screen, preferably through the medium of rods 39 and 40 having their outer ends respectively hingedly connected to the end of the lever and to the screen and having their inner threaded ends joined by a turn buckle sleeve 41. Conveniently the hinged connec-

tion between the rods 39 and their respective levers may be effected by providing a transversely extending axle or shaft 42 the ends of which respectively extend through bosses 5 31''' on the ends of the levers and other bosses 39' on the ends of the rods, collars 43 on the shaft serving to hold the parts in position. In a substantially similar way the connection between the rods 40 and the screen 10 may be effected, that is, through the medium of a transversely extending shaft 44 extended through bosses 40' on the ends of the rods and pillow blocks 45 carried by the screen, collars 46 serving to hold the parts in position. It will thus be apparent that the levers 31 are supported vertically by the flexible members which, in turn, are carried by the respective pairs of struts, while the rear end of the screen derives its support from the 20 free or rear ends of the levers through the medium of the rods and turn buckles; and further, that by adjustment of the turn buckles the angularity of the screen may be readily varied. In order to tie the struts 25 and upper ends of the flexible members together a tie bar 48 may be extended transversely through the latter and rigidly secured in position therein.

Means are provided for rapidly vibrating 30 or bending the flexible member to and fro in a horizontal plane and while any suitable means may be employed for that purpose, I prefer to extend a shaft 50 transversely of the members and support its ends for rotation in journals 51 securely bolted to the 35 flexible members substantially at their centers, this shaft being adapted to be driven at high speed in any convenient way as by a belt (not shown) passing over a pulley 52 mounted on a shaft. Upon this shaft I may 40 mount one or more elements 53 adapted to rotate with the shaft and each provided with a weight 54 which may preferably be made adjustable toward or from the center of the 45 shaft. Thus when the shaft carrying the unbalanced element or elements is rotated at high speed, a horizontal vibration will be set up in the flexible members so as to cause them to bend or vibrate to and fro as indicated by 50 the dotted lines in Fig. 1 with consequent vertical motion of the lower ends of the members which is, in turn, effective to raise the levers 31 from their normal position and return them thereto, or, in other words, to oscillate them about the shafts 33, since the 55 upper ends of the members are incapable of any movement whatsoever. Since the connection between the flexible members and the levers is at a point between the ends of the 60 latter and as the forward ends of the levers are hinged to the stringers, it will be apparent that the movement induced at the rear ends of the levers will be proportionately greater than the movement at their points of 65 connection with the flexible members, so that

a comparatively small vertical movement of the flexible members will result in a considerably greater movement of the free ends of the levers, which latter movement is transmitted directly to the screen. In consequence, the 70 extent to which the flexible members must be bent or flexed horizontally or, in other words, the amplitude of vibration which must be imparted to the members to induce or bring about a predetermined amplitude of vibration 75 in the screen, is relatively small, so that under operative conditions said members are not subjected to a bending or flexing moment sufficiently great to overcome their elastic limit and which might thus tend to cause them to break while, on the other hand, excessive unbalanced forces with consequent undesirable vibration and jar to the whole apparatus and the building in which it may be installed need not be employed in order 80 to effect a sufficient vibration of the screen to properly sift the material disposed thereon. Additionally, it will be observed that the angular inclination of the screen may be readily adjusted by means of the turn buckles 85 and that the whole apparatus is so constructed that there are no parts which are likely to become loose or get out of adjustment under operative conditions. This is an important 90 advantage of the apparatus since the constant vibrations which are set up in machines of this general character when in operation have a marked tendency to bring about a loosening of the parts if the same is possible.

While I have herein described and illustrated with considerable particularity a preferred embodiment of my invention I do not thereby desire or intend to in any manner limit myself specifically thereto as the design, construction and arrangement of the 100 various parts may be modified if desired from the precise forms to which I have referred without departing from the spirit and scope of the invention as defined in the appended 105 claims.

Having thus described my invention, I claim:

1. In a machine of the class described, the combination of a frame, a screen mounted on said frame and adapted for vibration with respect thereto, a flexible member rigidly secured at one end to the frame, means carried by and adapted to vibrate the member, and means carried by the frame and connecting the other end of said member and said screen, and arranged to impart to said screen an increment of the vibratory impulses generated in said member.

2. In a machine of the class described, the combination of a frame, a screen mounted to rock on said frame, a truss comprising relatively inclined struts mounted on said frame, a vibratile member supported by said truss and depending therefrom, a pivoted lever having a free end, means connecting said

member with said lever intermediate its ends and supporting means for said screen connected to the free end of said lever.

3. A machine as specified in claim 2 and comprising means for effecting vibration of the vibratile member in a horizontal direction.

4. In a machine of the class described, the combination of a support, an inclined screen pivotally mounted on said support, a flexible member, means adapted to generate vibratory impulses in a horizontal direction in said member, and means connecting said member and screen and arranged to transpose said vibratory impulses into magnified form and to direct them to said screen in a direction substantially normal to the plane of said screen.

5. A screen mounted on a supporting frame, a vibratile member carried by said frame, means to effect vibratory impulses in said member in a predetermined direction and means connecting said member and said screen arranged to transmit an increment of said vibratory impulses to said screen in another direction substantially normal to said screen.

6. An inclined screen supported at relatively spaced regions intermediate its length, a flexible member suspended at one end and carrying means for rapidly flexing or bending said member to and fro in a horizontal direction, and means carried by the frame and interposed between the other end of the mem-

ber and the screen for translating the resultant vertical component of movement of the free end of said flexible member to said screen in magnified amount and in a direction substantially normal to the plane of the screen.

7. An inclined screen supported at relatively spaced regions intermediate its length, a flexible member suspended at one end and carrying means for rapidly flexing or bending said member to and fro in a horizontal direction, and means carried by the frame and interposed between the other end of the member and the screen for translating the resultant vertical component of movement of the free end of said flexible member to said screen in a direction substantially normal to the plane of said screen, said translating means comprising a lever and link connection between the member and the screen arranged to transmit to the screen a greater vibratory movement than the total vertical component of the movement of said flexible member.

8. A machine as specified in claim 1 in which said connecting means include a lever pivoted at one end to the frame, an adjustable link extending from the other end of the lever to said screen, said flexible member being connected to the lever intermediate the ends of the latter.

In witness whereof, I have hereunto set my hand this 24th day of October, 1925.

HERBERT S. WOODWARD.
